UNITED STATES PATENT OFFICE.

GEORGE E. HEILIGMAN, OF HONDO, TEXAS.

CONCRETE TROUGH FORM.

Application filed July 10, 1925. Serial No. 42,847.

This invention relates to an improved form for round concrete troughs and seeks, among other objects, to provide a form of this character which may be readily set up and as easily removed after the trough has set.

The invention seeks, as a further object, to provide a form embodying inner and outer concentric shells, and wherein the circumference of the shells may be varied for forming different sized troughs.

And the invention seeks, as a still further object, to provide a novel brace for the inner shell and wherein means will be provided for expanding the brace to rigidly support the inner shell against collapse.

Other and incidental objects will appear hereinafter.

In the accompanying drawings:

Figure 1 is a top plan view showing my improved form in connection with a concrete trough.

Figure 2 is a vertical sectional view on the line 2-2 of Figure 1, looking in the direction indicated by the arrows.

Figure 3 is a detail sectional view showing the joint between the sections of the braces for the inner shell.

Figure 4 is an enlarged sectional view showing the expanding lever of one of the braces.

Figure 5 is a sectional view on the line 5-5 of Figure 4, looking in the direction indicated by the arrows.

In carrying the invention into effect, I employ an inner shell 10 and a somewhat wider concentric outer shell 11, which are preferably constructed of resilient sheet metal and, as shown in Figure 2, respectively comprise a long section which is somewhat over semi-cylindrical and a pair of like shorter sections. The sections of each shell are swingingly and detachably connected by pairs of butt hinges 12 disposed near the upper and lower edges of the sections, and by removing the hinge pins of the hinges at the ends of one of the short sections, said section may be displaced and the hinge plates at the free end of the remaining short section connected to the hinge plates at the adjacent end of the long section for thus contracting the shell. Accordingly, the shells may be employed to form different sized troughs.

Disposed within the inner shell is a pair of like annular braces 13 abutting the con-

fronting longitudinal edges of the pairs of hinges 12 of said shell and limited against displacement at the ends of the shell by said hinges. Each of said braces is of tubular construction and is formed preferably of a plurality of mating sections detachably connected with each other, as shown in Figure 3, by curved pins 14 fixed in corresponding ends of the sections. One of the sections of each brace is of a length corresponding to the length of the short sections of the inner shell respectively, so that when one of the short sections of said shell is removed for contracting the shell, the like short sections of the braces may also be removed, thereby adapting the braces to the smaller shell.

Screwed over one end of each brace, as shown in Figure 4, is a collar 15 having a slot 16, and formed in the opposite end of the brace is a series of spaced notches 17. Slidably fitting in the ends of the brace is a curved centering rod 18 provided near one end with a slot 19, and projecting at its forward end into said slot is a lever 20 which is freely received through the slot 16 of the collar 15 and is pivoted upon a rod 21 connecting the rod 18 with said collar. Pivoted upon the lever is a pawl 22, the free end of which is selectively engageable in the notches 17. Thus, the lever may be swung for spreading the ends of the brace apart and expanding the brace, and formed in the rod 18 is a series of openings 23 to selectively receive a pin 24 for locking the brace expanded.

In use, the shell 11 is placed upon a flat surface when cement is poured into the shell to form the bottom wall 25 of the trough. The shell 10 is then positioned concentrically within the shell 11 to rest at its lower edge upon said bottom wall, when the braces 13 are arranged within the shell 10 and expanded, as previously described, for rigidly bracing said shell and holding the shell in cylindrical shape. Additional cement is then poured into the annular cavity between the shells 10 and 11 to form the side wall 26 of the trough. The cement which forms the side wall is, of course, introduced while the cement of the bottom wall is still plastic so that said walls will integrally unite and, as will be seen, the cement of the side wall will, by its weight, press outwardly against the shell 11 to extend said shell to cylindrical shape so that the side wall of the finished trough will accordingly be formed with con-

centric inner and outer faces. When the cement has set, the braces 13 are first removed when the shells 10 and 11 are then, in turn, removed, to thus free the finished trough.

Having thus described the invention, what I claim is:

1. A brace for a concrete mold comprising complementary sections having the ends of adjacent sections hollow, a centering member having end portions detachably fitted within the hollow ends of the brace sections and extended across the gap formed therebetween, a lever pivoted to the centering member between the ends thereof, and a member pivoted at one end to the said lever and having its other end adapted to adjustably engage one of the brace sections.
2. A brace for a concrete mold comprising complementary sections having the ends of adjacent sections hollow, and having a plurality of external notches in the length of a hollow section, a centering member hav-

ing end portions detachably fitted within the hollow ends of the brace sections, a lever pivoted to the centering member and adapted to abut the end of a brace section, and a pawl pivoted at one end to the lever and adapted to have the opposite end coact with the notches of the other brace section.

3. A concrete trough form including a cylindrical outer shell, a cylindrical inner shell positioned concentrically within the outer shell, a split annular brace fitting in the inner shell, a collar fixed to one end of the brace, a centering rod carried by said collar and slidably received in the opposite end of the brace, and a lever pivoted upon said rod and provided with a pawl to coact with the latter end of the brace whereby the lever may be swung for spreading the ends of the brace apart and expanding the brace to rigidly coact with the inner shell.

In testimony whereof I affix my signature.

GEORGE E. HEILIGMAN. [L.S.]
